CONTINUOUS-FILM-TREATING APPARATUS

Albert W. Tondreau, Glendale, Calif., assignor to
Warner Bros. Pictures, Inc., New York, N. Y.,
a corporation of Delaware

Application May 2, 1938, Serial No. 205,577

15 Claims.

(Cl. 95—94)

This invention relates to film treating apparatus and has particular reference to apparatus for continuously developing, fixing, washing and otherwise treating the picture and/or sound track of motion picture film.

In treating motion picture film by passing it through various film treating solutions in a continuous manner, streaks frequently appear on the film, particularly during developing and fixing.

This is no doubt due to the fact that reaction compounds developed at the film emulsion surface by the chemical reaction between the chemicals of the treating solution and the film emulsion are drawn along the face of the film as it passes

15 through the treating solution due to skin friction and adherence. This drag of the reaction compounds effects an uneven development along the film and therefore produces streaks. Such streakage, when extending into the sound track portion of the film, produces a very noticeable distortion of the sound when reproduced.

Uneven treatment of the film is also caused by saturation of the treating solution immediately adjacent the emulsion surface of the film with spent portions of reaction compounds and other chemicals. This is true regardless of whether the film is being developed, fixed or rinsed.

One object of the present invention is to insure thorough and even treatment of the emulsion surface of a film while travelling through a film treating tank.

Another object of the invention is to prevent adjacent strands of a film passed in a series of elongated loops through a treating solution from coming in contact with each other, especially when under the impact of a flow of treating liquid directed onto the surface thereof.

Another object of the invention is to permit a maximum amount of film to be treated in a tank while preventing chemical drag along the emulsion surface thereof.

Another object of the invention is to facilitate removal of a film spraying jet unit from a film treating tank.

45 The invention contemplates apparatus for passing the film in a series of elongated loops through a film treating tank while directing a flow of film treating liquid, i. e. developer, fixer, water, etc., against the surface thereof to prevent chemical drag and to prevent the liquid directly adjacent the film surface from becoming saturated with the reaction compounds or other chemicals which form on the surface of the film and which are to be removed from the film. The invention also 50 contemplates roller means intermediate the ends

5 of the various film treating loops to support the film against the pressure of the liquid directed thereon and thus permits the use of relatively long elongated loops without the danger of the strands coming in contact with each other. Furthermore the invention contemplates a construction facilitating removal of a film spraying unit from a film treating tank for cleaning, replacing etc.

Although I am aware of the fact that film 10 treating solution has heretofore been sprayed onto the surface of a film, the present invention permits a much more compact and simple construction than heretofore available and also permits a greater amount of film to be treated by 15 the spraying system in any one tank than heretofore.

Although the invention is applicable to different types of film guiding arrangements for guiding the film through a treating solution, it is 20 particularly applicable to the type of film guiding apparatus disclosed and claimed in the co-pending application of A. W. Munson, filed July 28, 1936, S. N. 93,042, wherein film is guided in a plurality of elongated loops by two spaced parallel rows of spools, the axes of rotation of the spools in one row being arranged at 45° to the length of that row and at 90° to the axes of rotation of the spools in the other row.

The manner in which the above and other objects of the invention are accomplished will be readily understood on reference to the following specification taken in conjunction with the accompanying drawings wherein:

Fig. 1 is a sectional elevational view through a 35 film treating apparatus embodying the present invention.

Fig. 2 is a sectional plan view of a clamp for locking a film separating roller support in different positions and is taken along the line 2—2 40 of Fig. 1.

Fig. 3 is a side view of the clamp illustrated in Fig. 2.

Fig. 4 is a transverse sectional view through the film treating apparatus and is taken along 45 the line 4—4 of Fig. 1.

Fig. 5 is an enlarged sectional view, partly broken away, taken through one of the manifolds and a jet tube connected thereto.

Fig. 6 is a sectional plan view, with parts broken away, illustrating the connection between two adjacent manifolds and is taken along the line 6—6 of Fig. 1.

Fig. 7 is a sectional plan view, partly broken 55

away, of the film separating roller and is taken along the line 7—7 of Fig. 4.

Fig. 8 is a schematic elevational view of a portion of a fluid supply system which may be employed.

In Fig. 1 I have shown my invention as being embodied in tank sections 9 and 10 which may constitute part of a continuous film treating machine. For example, sections 9 and 10 may contain a film developing solution. The next succeeding sections (not shown) may contain a rinsing solution and succeeding sections may contain the fixing solution, rinsing solutions, etc.

Each tank section contains a rectangular frame 11 comprising spaced vertical channel members 12 and 13 adjacent either side wall of the tank section. The bars 14 and 15 are secured across the upper and lower ends, respectively, of the members 12 and 13. A pair of spool heads 16 and 17 are provided in each tank for vertical movement along the members 12 and 13. Each spool head comprises a cross bar 8 having vertical cross heads 18 and 19 suitably secured at either end thereof. Grooved rollers 20 and 21 are rotatably mounted at the upper and lower ends, respectively, of each of the cross bars 18 and 19 to guide the spool head along the flanged portion of the members 12 and 13. The upper spool heads are normally secured in a position adjacent the top of the tank by a suitable locking device such as a lever 27 pivoted on the shaft of roller 20 and adapted to engage one of a plurality of vertically spaced notches (not shown) along the member 12. When lever 27 is unlatched the spool head 16 may be raised for the purpose of inspecting the film thereon, or, in fact, may be raised completely clear of the frame 11 for cleaning, repairs, etc.

The various rectangular guide frames 11 in tank sections 9, 10, etc. are all suitably secured to a horizontal channel member 22 extending slightly above the upper edge of the various tanks and longitudinally of the film treating apparatus. As shown in Fig. 4, the channel member 22 is supported independently of the various tank sections upon a plurality of spaced arms one of which is shown at 23. Arm 23 is vertically adjustable in a suitable manner along a post 24 embedded in a foundation 25 which also forms a support for the bottom of the tank sections 9, 10 etc. This arrangement permits independent removal of the tanks or film guiding structure therein.

The film drive comprises a horizontally extending drive shaft 27 adjacent the channel member 22 and driven by a suitable motor (not shown). Film sprockets 28 and 29, individual to the tank sections 9 and 10, respectively, are provided to drive the film through these sections. These sprockets are rotatably mounted in drive units 30 generally indicated at 30 and 31, respectively, supported on the channel member 22 and are driven through suitable gear connections 32 and 33, respectively, from the drive shaft 27. A roller 34, rotatably mounted on the drive unit 31 adjacent the sprocket 29, is provided to guide the film from the tank section 9 onto the sprocket 29.

The above mentioned film drive and means for supporting the same and the film guiding structure independently of the tank is disclosed and claimed in my co-pending applications Serial No. 190,237, filed February 12, 1938, and Serial No. 193,966 filed March 4, 1938.

A row or set of adjacent film guiding spools 35 are rotatably mounted in a suitable manner upon the spool head 16. These various spools

35 have their axes of rotation lying in a common horizontal plane and arranged at 45° to the length of the bar 8.

The lower spool head 17 also has a row of film guiding spools 36 rotatably mounted thereon in a suitable manner. These spools 36 have their axes of rotation lying in a common horizontal plane but at 90° to the axes of rotation of the upper set of spools 35. The lower spools 36 are each vertically aligned with the upper spools 35 and the size and spacing of the same are such that the path of the film, as it passes from a lower spool 36 to an upper spool 35 extends directly vertically while twisting 90° from one spool to the next. This provision permits the strands 15 of the various film loops to lie parallel and adjacent each other forming a compact film path while obviating the side thrust or rubbing action of the film as it passes over the various film spools. This film guiding arrangement is disclosed and claimed in the above mentioned co-pending application of A. W. Munson.

As will be noted in Figs. 1 and 4 the film spraying system comprises a pair of jet manifolds 38 and 39 supported on the upper ends of the side walls 40 and 41, respectively, of each tank section. These various manifolds are flattened at the bottoms thereof as at 42 (Fig. 5) to permit the same to rest on the upper surface of their respective adjacent walls. Each manifold extends inwardly, overhanging the inner surface of its tank wall and has integrally formed therewith a plurality of spaced, downwardly projecting, hollow bosses 43 in which are suitably secured, as by welding, the upper ends of a plurality of jet tubes 44. 35 These various jet tubes depend from and are supported by their manifolds and extend vertically in the tank and terminate at the lower ends thereof in closure caps 45.

As shown in Fig. 1 the jet tubes 44 connected 40 to the rear manifold 38 are so spaced that each is directly adjacent one of the rear film strands 46 of the film loops in the film treating tanks. Also the jet tubes connected to the front manifold 39 are so spaced that each is directly adjacent one of the front film strands 49 of the film loops. A plurality of jets, two of which are shown at 47 and 48 (Fig. 5) are drilled in each jet tube 44 in vertical alignment with each other to direct parallel jets or streams of film treating liquid. 50 passed through the jet tube in the same plane onto the surface of the film as it moves therewith. That is, the axes of the various orifices or jets 47, 48 etc. substantially intersect the center of the path of the adjacent film strands. 55

Although any number of jets may be used, I have found that four substantially equally spaced jets in each tube are sufficient to accomplish the desired turbulence and anti-chemical drag effect. These jets are preferably about .045 inch in diameter, the liquid being forced therethrough under a pressure usually ranging from eight to twenty-five pounds per square inch.

It will be noted that the lower jet 48 in each of the tubes 44 is drilled co-extensively through both 65 the cap 45 and the wall of the tube 44, directly adjacent the end of the tube 44 so as to act as a drain, permitting all liquid within the tube 44 to be drained therefrom when desired. A tie bar 50 is provided to secure the lower ends of the 70 various jet tubes depending from the manifold 38 in spaced relation with each other. A second tie bar 51 is provided to secure the various tubes depending from the manifold 39 in spaced relation with each other. The various manifolds are 75

permitted to merely rest on the upper ends of their respective tank walls, the weight of the tubes 44 depending therefrom being sufficient to hold the manifold in a set position. However, 5 nails as at 53 may be provided to prevent the manifolds from being accidentally pushed into the tank.

As shown in Fig. 6 the adjacent ends of the various manifolds 38 and 38', individual to the 10 tank sections 9 and 10 and situated on the same side of the film treating tank, are connected together through rubber hose couplings 54. These 15 hose couplings 54 are fitted over sleeves 55 and 56 formed integrally with the ends of the manifolds 38, 38', etc., respectively. Suitable metal sleeve clamps as at 57 and 57' are provided to securely clamp the coupling 54 on the sleeves 55 and 56 so as to prevent leakage of the solution therebetween.

If the various jet tubes 44 and manifolds 38, 38' etc. are formed of metal which is different from that of the frame 11 the electrolytic or voltaic effect, produced by the chemical action between the film treating liquid in the tank sections, the 20 metal tubes 44, and the frame 11, is reduced by 25 electrically connecting these various manifolds and frames, the manifold 38 usually being grounded through metallic connection with grounded supply pipe 63. This may be done by welding or 30 otherwise metallically securing conductor strips 58 (Fig. 6) between the various adjacent manifolds. Also conductor strips 58' (Fig. 1) are metallically connected between the manifolds and the frames 11. These various conductors 58 and 35 58', however, are of very thin metal, permitting them to be broken or otherwise easily removed in the event that the manifolds are to be removed from their respective tank sections independently of each other and the frames 11.

The end of the rear manifold 38 opposite the 40 hose 54 is connected through an angle pipe coupling 60 to a vertically extending pipe 61 which, in turn, is connected through a cross pipe 62 to a main liquid delivery pipe 63 through a T-connection 64. It will be noticed, of course, that in 45 case the treating liquid is to be supplied only to the two tank sections 9 and 10 the manifold 38' will be closed at the end thereof (not shown) opposite the hose coupling 54. In this case the 50 corresponding end of the front manifold (not shown) in tank section 10 will also be closed. The front manifold 39 is connected by means of an angle pipe coupling 65 and a vertical pipe 66 to the T-connection 64, thus permitting equalized 55 pressure within the manifolds 38 and 39 and consequently in each of the tubes 44. Film treating liquid is supplied to the delivery pipe 63 under pressure from a suitable source of supply. When the various rear manifolds 38, 38', etc. and jet 60 tubes 44 attached thereto are placed in the respective treating tanks the manifold 38 in tank 9 is first rigidly attached to the supply coupling 65 in such a manner that lower ends of the jet tubes 44 depending therefrom are in contact with the 65 adjacent wall 40. The next manifold 38' in tank 10 is then placed in position with the rubber hose coupling 54 fitted over the sleeves 55 and 56 of manifolds 38 and 38'. Clamp 57 is then clamped on the hose 54 over the sleeve 55 to secure the 70 hose to the manifold 38. Thereafter, the hose 54 is twisted about the axis thereof under sufficient torsion and secured by clamp 57, while under torsion, to the sleeve 56 of manifold 38'. The twist of hose 54 is in such a direction that the 75 jet tubes 44 depending from manifold 38' are

urged against the adjacent side wall of tank section 10. The front manifolds 39, etc. are connected in a similar manner thus insuring that the lower ends of the tubes 44 are retained in contact with the adjacent walls of the tank sections. 5

Overflow pipes are connected to each of the tank sections to drain off the treating liquid therefrom as it fills the tanks and approaches the top edges thereof. These overflow pipes, one of 10 which is shown at 106 (Fig. 4), have their openings situated approximately level with the upper spool head 16, when in its normal position, so as to retain the film in a submerged position throughout its travel through each tank section. The position of the jets 47, 48 etc., as well as the 15 film itself, below the level of the treating fluid in the various tanks reduces aeration of the treating liquid, thus preventing oxidation and consequent breakdown of the treating liquid, especially the developing liquid. Preferably the 20 treating liquid drained through the overflow pipes 106 is re-circulated in a manner not shown by 25 passing the same under pressure through the supply line 63 and thereafter back through the jet tubes 44.

To prevent the various strands of the elongated loops of film passing between the spool heads 16 and 17 in each tank section 9, 10, etc. from being 30 forced into contact with each other, or from flapping excessively due to the pressure of the various jets of film treating liquid directed thereon, a pair of co-axial film separating rollers 67 and 68 are provided intermediate the spool heads 16 and 17. These two rollers 67 and 68 have the adjacent 35 ends thereof located close to each other and they extend the entire horizontal length of the looped path of the film intermediate the front and rear strands of each loop so as to engage all strands of the film, the films resting flat against the rollers. These two rollers 67 and 68 are hollow 40 and are rotatably supported on a single shaft 69. Ball bearing mounts 70 and 71 are provided within each roller to rotatably support the same on the shaft 69. Shaft 69 is supported intermediate the adjacent ends of the rollers 67 and 68 by a bracket 72 provided on the lower end of a vertically adjustable rod member 73. Rod 73 extends above the top of the respective tank section and is adjustably secured within a clamp 45 generally indicated at 74 (Figs. 2 and 3). Clamp 74 comprises a casting 75 adjustable along the upper flanged portion of the channel member 22 and is adapted to be secured in any adjusted position by a lock screw 76. A vertically extending 50 groove 77 at the front of casting 75 forms a guide for one edge of the rod 73. The other edge of the rod 73 is guided by means of a grooved guide member 78 hinged for movement about a vertical axis on a pin 79 carried in lugs 80 and 81 extending from and integrally formed on the casting 75. A clamp screw 82 passing through an enlarged aperture in the member 78 and threaded within the casting 75, is provided to permit the guide member 78 to be swung open, thereby allowing transverse removal of the rod 73 from the clamp 74 when desired. Rod 73 has a plurality of spaced notches 83 (Fig. 1) therealong, any one of which is adapted to be engaged by a latch 84 pivotally mounted on a lock screw 85 threaded 55 into the top of the casting 75. Screw 85 is adapted to lock the latch 84 in engagement with any one of the notches 83.

When the front manifold and jet tube assembly is to be removed from its respective tank section 76

for cleaning, repairs, etc. the hose coupling as at 54 and the pipe connection 65 (if the assembly is located in tank section 9) and conductor strip 58 are removed permitting the assembly to be 5 raised clear of the tank. If the rear manifold and jet tube assembly is to be removed, however, the upper spool head 16 is first removed from the frame 11 by raising the same clear of the guide members 12 and 13. The guide member 78 on the 10 clamp 74 is then swung open permitting the rod 18 and separating rollers 67 and 68 to be removed from the tank section. The rear manifold and jet tube assembly is thereafter detached from the hose coupling 54, conductor strip 58 and pipe connection 65 (if the assembly is located in tank 15 section 9) and raised clear of the tank.

When the length of the film path within any of the tank sections is to be changed, for example, for varying the time of film development or 20 film treatment, the film is removed from the entry film sprocket, i. e. sprocket 28 for tank 9, and is held while the exit film sprocket for that tank section, i. e. sprocket 29, continues to feed the film into the next succeeding tank section. 25 This causes the film to raise the lower spool head 17 to any desired level. After the spool head 17 is raised a desired amount the film is replaced on the entry sprocket 28 to retain the length of the film path constant. In order to position the rollers 67 and 68 midway between the spool heads 16 and 17 in a newly adjusted position of the spool head 17, the latch 84 of clamp 74 is moved outwardly out of engagement with the notched rod 73 permitting the rod to be raised upwardly 30 until the rollers 67 and 68 assume their correct position. The latch 84 is then engaged with the nearest notch 83 in rod 73 to hold the rollers in that position.

Fig. 8 illustrates one arrangement of fluid supply for film treating tanks in which the present invention may be embodied. This arrangement is disclosed and claimed in co-pending application of Fred W. Gage Serial No. 217,453 filed July 5, 1938, for "Film processing apparatus" and comprises a plurality of tanks or tank sections 86, 87, 88, 89, 90 and 91. Manifold and jet tube assemblies 92, similar to those of 38 and 39, are provided for each tank section. If desired only one manifold and jet tube assembly may be employed 50 for each tank section instead of two as shown in Figs. 1 and 4. Film treating liquid is passed under pressure through a supply line 93 into the manifold assembly 92 of the last tank section 91, the film being passed successively through the 55 various tank sections 86 to 91, inclusive, in the direction of the arrow A. The film treating solution is fed into the next preceding manifold of the tank 90 through a hose coupling 94. The film treating liquid is sprayed from the various jet 60 tubes (not shown) depending from the manifolds in these tank sections and overflows through pipes 95 and 96 similar to that of 106 (Fig. 4). It will be understood that the various tank sections are filled with treating liquid to the level 65 of the openings of the overflow pipes 95 and 96 and that the various jet tubes are submerged in this liquid. Pipe 96 is connected to pipe 95 which, in turn, is connected to the suction opening of a pump 97 driven by a suitable motor 98. 70 A pressure pipe line 99 connected to the pressure opening of the pump 97 connects the same with the manifolds 92 of the tank sections 88 and 89 to feed the film treating liquid thereto. The overflow pipe lines 100 and 101 therefrom 75 are connected together and feed into the suction

opening of a second pump 102 also driven by the motor 98. A pressure line 103 feeds the solution from the pressure opening of the pump 102 to the manifolds of the tank sections 86 and 87. The overflow lines 104 and 105 from these tank 5 sections 86 and 87, respectively, conduct the solution therefrom to either a suitable filtering and re-circulation system or to the sewer. This arrangement is particularly advantageous in washing the film since the film in the last tank section 10 91 receives the cleanest portion of the rinse water.

I claim:

1. Film treating apparatus comprising two spaced sets of film spools for guiding a film thereover in a looped path, the axes of rotation of the spools in one of said sets being disposed at substantially 45° to the length of said set and at substantially 90° to the axes of the spools in the other of said sets, means forming jets for directing film treating liquid against the surface of the film on opposite sides of said film path, a roller intermediate said sets of spools and adapted to be engaged on diametrically opposed points on the circumference thereof by the opposite strands of each of a plurality of loops of said film, and means for rotatably supporting said roller.

2. Film treating apparatus comprising a pair of vertically spaced spool heads adapted to guide a film in a looped path therearound, means adapted to direct a plurality of streams of film treating liquid against the opposite strands of the loops of film in said path, a plurality of co-axial rollers parallel to and intermediate said spool heads, said rollers being adapted to be engaged on diametrically opposed points on the circumference thereof by the opposite strands of a plurality of loops of said film to support said film against the pressure of said streams of film treating liquid, and a common support for rotatably supporting said rollers.

3. Film treating apparatus according to claim 2 comprising means whereby said rollers may be moved toward and away from one of said spool heads.

4. Film treating apparatus comprising a pair of vertically spaced spool heads adapted to guide a film in a looped path therearound, means adapted to direct a plurality of streams of film treating liquid against opposite strands of the loops of film in said path, a pair of co-axial rollers extending parallel to and intermediate said spool heads, said rollers being adapted to engage on diametrically opposed points on the circumference thereof the opposite strands of each of a plurality of loops of said film to support said film against the pressure of said streams of film treating liquid, a common shaft for rotatably supporting said rollers, a vertically extending rod member, means securing said rod member at the lower end thereof to said shaft at a point intermediate said rollers, and means for supporting said rod at the upper end thereof.

5. Film treating apparatus comprising means 65 adapted to guide a film in a looped path containing a plurality of loops, means adapted to direct a plurality of streams of film treating liquid against the film in said path, a pair of co-axial rollers intermediate the ends of said loops and 70 having their axes extending substantially normal to the direction of travel of the film strands in said loops, a common shaft for rotatably supporting said rollers to support said film against the pressure of said streams of film treating liquid, 75

and means for supporting said shaft at a point intermediate said rollers.

6. Film treating apparatus comprising two parallel rows of film spools, means for rotatably supporting the spools in one of said rows with the axes thereof at substantially 45° to the length of said row, means for rotatably supporting the spools in the other of said rows with the axes thereof at substantially 90° to the axes of the spools in said first mentioned row whereby a film may be passed from the spools in one of said rows to the spools in the other of said rows with the emulsion surface thereof out of contact with said spools while twisting substantially 90° from one spool to the next, means forming jets on one side of said row for spraying the emulsion surfaces of the film strands adjacent said side, and means forming jets on the opposite side of said row for spraying the emulsion surfaces of the film strands on said opposite side.

7. Film treating apparatus comprising the combination of a tank, two parallel vertically spaced rows of film spools for traversing film through said tank, the axes of rotation of the spools in one of said rows being angularly disposed in a horizontal plane at substantially 45° to the length of said row, the axes of rotation of the spools in the other of said rows being angularly disposed in a horizontal plane at substantially 90° to the axes of rotation of the spools in said first mentioned row, whereby a film may be passed from the spools in one of said rows to the spools in the other of said rows with the emulsion surface thereof out of contact with said spools while twisting substantially 90° from one spool to the next, said film forming two rows of strands lengthwise of said tank, jet tubes for said film and positioned between one of said rows of strands and the adjacent side of said tank, and means for supplying liquid under pressure to said jet tubes.

8. Film treating apparatus comprising a tank, a frame in said tank, a pair of spaced spool heads supported on said frame, spools rotatably carried by said heads, said spools being adapted to guide a film thereover in a plurality of loops extending from one of said spool heads to the other, a plurality of conduits in said tank, means for supplying film treating liquid to said conduits, said conduits having jet orifices therein adapted to direct said film treating liquid towards said film to impinge on the surface thereof, means for removably supporting said frame in said tank, and means for removably supporting said conduits in said tank independently of said frame and said first mentioned supporting means whereby said conduits may be removed from said tank inde-

pendently of said frame, and vice versa, and a removable electrical conductor connecting said conduits and said frame.

9. Film treating apparatus comprising a tank, means for passing a film through said tank, a manifold resting on an upper edge of said tank, jet tubes connected to and supported by said manifold, and means for supplying film treating liquid to said manifold, said tubes extending into said tank and having jet orifices therein to direct streams of said film treating liquid from said tubes onto the film passing through said tank.

10. Film treating apparatus comprising a film treating tank, a manifold having a flat bottom portion resting on an upper edge of said tank, and jet tubes depending from said flat bottom portion and communicating with and supported by said manifold, said tubes extending into said tank and having jet orifices therein.

11. Film treating apparatus comprising a pair of spaced spool heads adapted to guide a film through a plurality of elongated loops, each strand of each of said loops twisting substantially 90° throughout the length thereof, and jet means on each side of each of said loops for spraying each of said strands at spaced points therealong.

12. Film treating apparatus comprising a film treating tank, means adapted to guide a film through said tank, a manifold above one wall of said tank and extending parallel to said wall, jet tubes depending from said manifold into said tank adjacent the inside of said wall, and a liquid supply pipe depending from said manifold adjacent the outside of said wall.

13. Film treating apparatus comprising a tank, means adapted to guide a film through said tank, a manifold resting on top of said tank, jet tubes depending from said manifold into said tank, a flexible liquid supply conduit for said manifold and means for attaching said conduit under torsion to said manifold whereby the lower ends of said tubes are urged against one side of said tank.

14. Film treating apparatus comprising a plurality of aligned tank sections, means for guiding a film through said tank sections, a manifold individual to and adjacent each tank section, jet tubes extending from said manifolds to their respective tank sections, conduits removably coupled between adjacent ones of said manifolds, and means for supplying film treating liquid to one of said manifolds.

15. Film treating apparatus according to claim 14 wherein said conduits comprise insulating material, and electrical conductors connected between adjacent ones of said manifolds.

ALBERT W. TONDREAU.
